Filed Feb. 12, 1973, Ser. No. 331,364

Term of patent 14 years

Int. Cl. D6—08

U.S. Cl. D6—247

FIG. 1 is a perspective view of the trouser hanger showing the design thereof;

FIG. 2 is a transverse vertical section thereof, taken along the line 2—2 of FIG. 1;

FIG. 3 is a view of the open end thereof;

FIG. 4 is a transverse vertical section thereof, taken along the line 4—4 of FIG. 1;

FIG. 5 is a view of the closed end thereof;

FIG. 6 is a top plan view thereof;

FIG. 7 is a front elevation thereof; and

FIG. 8 is a bottom plan view thereof.

For ease of illustration, the hook portion of the trouser hanger has been shown broken away in FIGS. 2, 4, 5, and 7.

I claim:

The ornamental design for a trouser hanger, as shown and described.
